UNITED STATES PATENT OFFICE.

JULIUS MANY, OF NEW YORK, N. Y.

COMBINED TIRE-VALVE AND PRESSURE-INDICATOR.

1,377,596.

Specification of Letters Patent. Patented May 10, 1921.

Application filed July 26, 1920. Serial No. 398,966.

To all whom it may concern:

Be it known that I, JULIUS MANY, a citizen of France, residing at 163 E. 92nd St., New York, in the county of New York and State of New York, have invented certain new and useful Improvements in a Combined Tire-Valve and Pressure-Indicator, of which the following is a specification.

My invention relates to a combined tire valve and pressure indicator.

One of the objects of my invention is to provide an indicator for the pressure in the inner tube of a pneumatic tire which shall not be entirely dependent upon the action of a coil spring.

Another object of my invention is to provide such an indicator in which the resilient element shall be protected from dust, oil and the like.

Other objects of my invention will be set forth in the following description and drawings which illustrate a preferred embodiment thereof.

Figure 1 is an elevation partially in section.

Fig. 2 is a vertical central section.

Fig. 3 is an enlarged vertical central section of parts of the device.

Fig. 4 is a section along the line 4—4 of Fig. 3.

Fig. 5 is a section along the line 5—5 of Fig. 3.

Fig. 6 is a section along the line 6—6 of Fig. 3. All the sectional views are taken in the direction of the arrows adjacent their respective lines.

The combined valve and indicator has a base portion 4 which is externally threaded and which is provided with a flange 2 at the lower end thereof.

As can be seen in Fig. 1 in particular, the cross section of the base portion 4 is not circular, but parts of the original circular body thereof have been cut off so as to form two opposite and parallel plane faces, one of which is shown in Fig. 1, the other plane face being opposite thereto. These faces have no threading.

The slide 3 which has the shape of the base 4 except that it is made wide enough so as to be able to slip over its threading is mounted above the flange 2.

As shown in Figs. 1 and 2, the inner tube can be held between the slide 3 and the flange 2, and by screwing down the nuts 21 and 30 which coöperate with the exterior

threading of the base 4, the inner tube 1 can be firmly clamped in position.

A cap 5 having a hexagonal head 6 can be screwed down upon the base 4 so as to cover the working parts of the device, which will be further described. The base 4 which is provided with a bore 7 is extended so as to form a neck 23 which is provided with a scale as shown in Fig. 3, so as to indicate the pressure within the inner tube in pounds per square inch or in any other desired unit.

A slide tube 8 which is externally threaded at its upper end as shown in Fig. 3, is mounted upon the neck 23 and is adapted to slide up and down thereon.

A coil spring 9 is mounted within the slide tube 8 as shown in Figs. 2 and 3, its bottom resting against the bottom of the slide tube 8, and its upper end bearing against the cylindrical flange 10 of the resilient hook member 12, which as seen in Fig. 3 is provided with an externally threaded projection 24 having a bore 22, the said projection 24 being fastened to the neck 23 by means of suitable coöperating threading.

The tendency of the weak coil spring 9 is therefore to force the bottom of the slide tube 8 to the bottom of the scale provided upon the exterior of the neck 23.

Above the flange 10, the hook member 12 is split so as to provide four resilient hook-like members as shown in Fig. 5 whose outwardly turned ends press against the bushing 11 whose exterior surface is cylindrical so as to fit snugly against the inner surface of the slide tube 8 and whose inner surface has a conical shape, the narrowest portion of the inner surface of the bushing 11 being at the bottom or the base portion thereof. By base portion is meant that part which is nearest the inner tube when the device is in use.

As seen in Fig. 3, the bushing 11 may be provided with an upward flange at the upper part thereof, which may fit over the top of the slide tube 8.

A washer holder 14 having an internal bore 15 is mounted within the hook member 12 so as to be firmly held in position and to fit tightly. The bottom of the washer holder 14 fits snugly against the adjacent part of the hook member 12.

The washer holder has a seat 16 for the resilient washer 17 which has a dish shape and is provided with holes 22.

A ball valve 18 is pressed by the resilient

washer 17 against the bore 19 of the pump member 20 whose threaded head 25 is secured over the slide tube 8 by suitable co-operating threading as shown in Fig. 3.

5 The action of my device is as follows:

When the parts are assembled in the positions before described, the nozzle of the air pump can be secured to the pump member 20 and air can be forced in in the usual 10 way. The pressure of the incoming air slightly displaces the ball valve 8 and the air passes through the bores of the various members before described into the inner tube.

15 As soon as the pressure from the air pump is removed, the resilient washer 17 forces the valve 8 into its closed position, and the pressure of the air within the inner tube tends to seat the valve 8 more tightly and 20 to close the bore 19 more tightly so as to prevent the escape of the air.

The pressure of the air within the inner tube against the ball valve 8 tends to force the pump member 20 together with the slide 25 tube 8 to which it is secured away from the base 4.

This tendency is resisted to a very slight degree by the coil spring 9, the substantial resistance being offered by the four hooks 30 or claws of the split member 12 which are forced together by the movement of the bushing 11, which is carried along by the slide tube 8.

The substitution of the split claw member 35 12 which presses against the conical inner surface of the bushing 11, provides a resilient means to oppose the pressure of the air within the inner tube which is not dependent upon temperature, atmospheric conditions and the like.

In addition, the resilient means is perfectly inclosed against oil, dirt and the like.

The slide tube 8 is forced upwardly or away from the base to an extent depending 45 upon the pressure within the inner tube, and the distance to which the bottom of the slide tube rises, with respect to the scale upon the neck 23 indicates the pressure within the inner tube.

50 The device thus serves as a combined valve and pressure gage.

I have described a preferred embodiment of my invention, but it is clear that numerous changes and omissions could be made 55 without departing from its spirit.

If desired, washers or any suitable packing members of known type can be used between the various metal members before described, to prevent leakage. This feature 60 is not disclosed in the drawings, because in itself it is old and well-known.

I prefer to have a minute perforation in the neck 23 above the scale, so that if the pressure rises above the safety point for 65 any reason, so that the bottom of slide tube

8 rises above the scale, the air can escape. This perforation is not shown in the drawings, as the scale thereof is too small.

The bushing 11 could be made just long enough to permit the claw member 12 to contact therewith at all times. The washer holder 14 could be connected to bushing 11 by any suitable holding means, to further keep it steady during the operation of the device. 75

I claim:—

1. In combination, a base portion, means for securing it to the inner tube of a tire, a scale connected to said base portion, a slide 80 member mounted to slide to and fro on said base portion, a resilient member having resiliency in a direction transverse to the movement of said slide member, means for securing it to said base portion, and means intermediate said slide member and said resilient member whereby the movement of the slide member affects the transverse contour of said resilient member, and connections intermediate said slide member and said inner tube whereby the pressure of the air in said inner tube tends to actuate said slide member. 85

2. In combination, a base portion, means for securing it to the inner tube of a tire, a resilient member having resiliency in a direction transverse to the axis of said base portion, an indicating member mounted on said base portion adjacent said scale and adapted to co-operate therewith, and connecting means 95 intermediate said resilient member and said indicating means whereby the movement of said indicator affects the transverse contour of said resilient member and connections intermediate said indicating member and said inner tube whereby the pressure of the air in said inner tube tends to actuate said indicating member. 100

3. In combination, a hollow base-portion means for securing it to an inner tube of a tire, said base portion having a scale secured thereto, a slide tube fitting over said scale and adapted to move with respect to said scale, a resilient member secured to said base portion above said scale and adapted to 110 resist the movement of said slide member away from the base of said base portion, and a check valve located above said resilient member and connected to said slide member so that the air pressure in said inner tube tends to move said slide member away from said inner tube. 115

4. In combination, a hollow base portion having a relatively narrow neck provided with a scale on the exterior thereof, a slide tube mounted on the exterior of said neck and adapted to be moved up and down on said scale, an interior bushing connected to said slide tube and having an inner conical surface with its smallest cross-section di- 125 130

ameter adjacent said scale, a split resilient member secured to said neck and extending within said bushing and having resilient arms bearing against the interior surface 5 thereof, and a check valve located above said bushing and secured to said slide tube, so that the pressure of the air in said inner tube tends to force said slide tube along said scale and to force the resilient arms to 10 together.

5. In combination, a hollow base portion having a relatively narrow neck provided with a scale on the exterior thereof, a slide tube mounted on the exterior of said neck 15 and adapted to slide up and down on said scale, a bushing fitting over the top of said slide-tube and located above said scale said

bushing having an interior conical surface which tapers toward said scale, a split resilient member secured to the top of said neck 20 and having resilient arms which bear against the interior surface of said bushing, a valve support extending above said bushing and carrying a resilient dished washer provided with perforations, a valve 25 carried by said washer and pressed by said washer against the end of the bore of a pump-connection member which is secured to the top of said inner tube, whereby the pressure of the air in said inner tube tends 30 to force said slide tube along said scale.

In testimony whereof I hereunto affix my signature.

JULIUS MANY.
